UNITED STATES PATENT OFFICE.

SAMUEL C. RUGLAND, OF SAN FRANCISCO, CALIFORNIA.

TAILOR'S PRESS-PAD.

SPECIFICATION forming part of Letters Patent No. 325,277, dated September 1, 1885.

Application filed October 22, 1884. (No model.)

To all whom it may concern:

Be it known that I, SAMUEL C. RUGLAND, a citizen of the United States, residing at San Francisco, in the county of San Francisco and 5 State of California, have invented a certain new and useful Tailor's Press Pad for Pantaloons, of which the following is a specification.

My invention relates to an improved press-pad for the use of tailors in pressing out and 10 giving form and set to the bottom of pantaloons-legs; and the object of my improvements is to provide a press-pad capable of lateral extension and contraction, and one which will at all times present a smooth and even external surface. I attain this object by the mechanism illustrated in the accompanying drawings, in which—

Figure 1 is a plan view of my improved press-pad. Fig. 2 is an end view of the inner 20 end of the press pad. Fig. 3 is a face view of the outer end of the press-pad. Fig. 4 is a face view of the outer end of the press-pad, partially broken away, and showing the thumb-wheel removed. Fig. 5 is a cross-sectional view. Figs. 6 and 7 are detail views. Fig. 8 is a plan view showing the interior of the upper half or face of the press-pad. Fig. 9 is a plan view showing the lower half of the press- 25 pad.

Similar letters of reference are used to designate like parts throughout the several figures.

My present invention consists of an improvement upon the device for which Letters 30 Patent of the United States were granted to me on the 16th day of September, 1884, No. 305,112, for an improved press-pad for pantaloons, and it relates more particularly to certain details of construction, whereby the pad 35 is made extensible and the cloth covering drawn taut, as will be more fully explained hereinafter.

My improved press-pad consists of four pieces of sheet metal, A, B, C, and D, bent 40 into the form shown in the drawings, the upper and lower sections moving upon each other, and the front and rear sections being capable of being advanced toward or retracted from each other, as the requirements of the 45 case may demand. The rear or outer sections, A and B, are connected together near either end of their rear edge by means of the

metal tongues E and F and screws or rivets G, which rivets G also pass through a division plate or rib, to be hereinafter more fully 55 described. The front or inner sections, C and D, are connected together at their ends by the plates H and I, which form the bearing or journal plates for the operating shafts.

In order to hold the front edges of the outer sections down snugly upon the outer faces of the inner sections, I provide the said inner sections with a series of transverse slots, J J, through which pass pins K K, riveted in the 6 outer sections, and all connected together on each inner face of the inside sections by a strip of strap-iron, L, which prevents the withdrawal of the said pins or rivets K K from their slots and hold each upper and lower section 70 of the pad closely in position.

Near each end of the front or inner sections, C and D, and upon the inside horizontal faces thereof, I attach the flanged guides M M, within which are reciprocated the flat bars or 75 plates N N, provided upon their faces with the toothed racks O O, and firmly attached at their outer ends by solder, to the rear or outer sections, A B, while their inner ends are left 80 perfectly free and loose.

P is the main operating-shaft, and is journaled in the end plates, H and I, and is provided upon the inner side of its bearings with cog-wheels Q Q, which mesh with the intermediate cogs or pinions, R, mounted upon a 85 shaft, S, which also has its end bearings in the end plates, H and I. The pinions R mesh with the racks on the upper outer plate, A, while the cogs or pinions Q mesh with the racks on the lower outer plate, B, as clearly 90 shown in Fig. 5. One end of the main shaft P is provided with a ratchet-wheel, T, and pawl T', controlled by a spring, U, for the purpose of holding the inner or front and outer or rear sections or plates in any set position, 95 and this shaft is also provided with a thumb-wheel, V, for conveniently rotating the said shaft.

Extending parallel with the shaft P, I journal in the end plates of the press-pad the two 100 shafts W and X, provided with a cog-wheel, W' and X', which mesh with the racks O O, as shown in Figs. 8 and 9. Upon each of these two last-named shafts I key the winding-

drums Y, of which any desirable number may be used, and upon them are wound the tapes Z, attached to the cloth covering of the press-pad. The said cloth covering A' is attached 5 to the front meeting-edge of the inner or front sections, C and D, and lays flat over the outer surface of the press-pad, and may be stitched to the ends of said section, if so desired.

Both pieces of cloth are then doubled or folded 10 over the outer edges of the outer or rear sections and passed through the space left between the said sections and the metal fastening-tongues E and F and carried into the body of the pad, as shown in Fig. 5. The loose 15 ends of these cloths are braced by being stitched to a wire rod, G', and are then attached by the tapes to the winding-drums. The dividing plate or rib, one end of which is shown in perspective in Fig. 7, consists of two plates of 20 metal, H' and I', joined together in such a manner as to form a T when viewed in cross-section. The plate which forms the top of the T is pierced at each end with a hole for the passage of the screws G, and is also pro- 25 vided with a lug or washer upon its inner face, which washer J' is used to hold out the top of the T from the rear edge of the outer sections, A and B, so as to permit of the free passage 30 of the cloth covering, and at the same time to fill out the concave space left between the upper and lower section and present a full, smooth, and even surface for the cloth of the pantaloons to rest against and prevent the creasing of the same. The plate I' extends for a short 35 distance within the body of the press-pad and serves as a strengthening-rib to the plate H', and also as a dividing-strip between the two pieces of cloth.

The manner of operating my improved 40 press-pad will be as follows, to wit: The pantaloons having been brought into a proper condition for pressing and receiving the proper "set" at the bottoms of the legs, the press-pad is to be inserted at the bottom of the leg, 45 and the thumb-wheel V is revolved, which will spread the two front and rear sections of the pad farther apart, and at the same time produce or cause the unwinding of the tapes and

the slackening of the cloth covering, which 50 unwinding and slackening keeps pace with or progresses at the same rate of speed at which the sections of the press-pad are forced apart, and thus the cloth covering is caused to lie flat and smooth upon the metal surface of the pad, and without any wrinkles to obstruct 55 the action of the smoothing-iron, or to crease the cloth during the process of pressing.

From the above it will be seen that I am 60 enabled to produce a cheap and durable press-pad for tailors' use, and one which is extremely simple in its construction and easy of operation, and in which the unwinding of the tapes of the covering-cloth is accomplished at the same time and by direct contact with the mechanism by which the extension or contraction of the pad is accomplished; and also to 65 close up the entrance or passage-way for the cloth covering into the body of the press-pad in such a manner that a smooth and even rear edge of the pad will be presented to the cloth 70 of the pantaloons, and creasing will be prevented.

Having thus described my invention, what I claim, and desire to secure by Letters Patent, is—

1. In an extensible cloth-covered press-pad for tailors' use, the combination, with the adjustable sections A, B, C, and D, of the metal fastening-tongues E F, division-plate H', and screws G, substantially as described.

2. In a tailor's press-pad, the combination of the sections A, B, C, and D, the end plates, H I, bars N N, having racks O O, the shafts P S, carrying pinions Q R, the shafts W X, carrying winding-drums Y Y and provided 85 with pinions W' X' that are driven directly by the racks O O on the upper and lower plates of the pad, the cloth covering A', and the dividing-plate H', substantially as described.

In testimony that I claim the foregoing I have hereunto set my hand and seal.

SAMUEL C. RUGLAND. [L. s.]
